COMBINED JEWELRY BOX AND TIE RACK

Jeffrey S. Snyder, 535 E. 86th St.,
New York, N.Y. 10021

Filed Jan. 17, 1972, Ser. No. 218,641

Term of patent 14 years

Int. Cl. D3—01

U.S. Cl. D87—1 B

Fig. 1

Fig. 2

Fig. 3

Fig. 4

Fig. 5

Fig. 6

Fig. 7

FIG. 1 is a front elevational view of a combined jewelry box and tie rack showing my new design;

FIG. 2 is a side elevational view thereof;

FIG. 3 is a top plan view thereof;

FIG. 4 is a bottom plan view thereof;

FIG. 5 is a rear elevational view thereof;

FIG. 6 is a top plan view thereof, showing the combined jewelry box and tie rack in open condition; and

FIG. 7 is a side elevational view thereof, showing the side opposite that seen from FIG. 2, and the combined jewelry box and tie rack in open condition.

I claim:

The ornamental design for a combined jewelry box and tie rack, substantially as shown.
